UNITED STATES PATENT OFFICE.

CHARLES EMMETT WEISNER, OF DURMID, VIRGINIA.

CUTTING MECHANISM FOR CIGARETTE MACHINES.

Application filed April 26, 1923. Serial No. 634,808.

To all whom it may concern:

Be it known that I, CHARLES E. WEISNER, a citizen of the United States, residing at Durmid, in the county of Campbell and **5** State of Virginia, have invented new and useful Improvements in Cutting Mechanism for Cigarette Machines, of which the following is a specification.

This invention relates to a cutting mechanism for cigarette machines and it has for its object to provide an improved cutting mechanism adapted to be used in connection with any type of cigarette machine in which the cigarette is discharged in the form of a **10** continuous rod or roll, means being provided whereby the roll is neatly cut perpendicular to its longitudinal axis into uniform lengths by a revoluble helical cutter, the axis of which is inclined both horizontally and vertically with respect to the cigarette roll to be cut. The roll is positively fed in unison with the operation of the revoluble cutter, and the carrier which feeds the roll is provided with ledger blades which cooperate **15** with the helical cutter and may be adjusted towards or from the same to vary the tension between the cutting means.

The invention will be more specifically described in connection with the accompanying drawings, in which:—

Figure 1 is a side elevation of the rear portion of a cigarette machine embodying the invention.

Fig. 2 is a plan view of the same.

Fig. 3 is a front elevation of the same.

Fig. 4 is a detail view of the means for adjusting the cutter.

Fig. 5 is a detail view showing the relation of the helical cutter to the cigarette **40** roll.

Fig. 6 is a detail sectional view of one of the ledger blades.

Fig. 7 is a detail view of the same.

In the drawings, 10 designates the rear part of a cigarette machine which may be of any desired construction wherein the cigarette is delivered in the form of a continuous roll. Journaled in the frame 10 are two spaced parallel shafts 11 and 12 on **45** which are mounted sprocket wheels 13 and 14, respectively. The shaft 12 is provided with a spur gear 15 by means of which it is positively driven from a gear 16 connected with the cigarette making machinery. A **50** sprocket chain 17 is carried by the sprocket

wheels 13 and 14, and a suitable means may be provided for tightening the chain by adjusting the bearing 18 for the shaft 11.

The chain 17 is provided with a series of blocks 19, each of which has a semi-cylindrical groove 20, formed in its outer face, which grooves form throughout the upper lap of the chain a substantially continuous groove which receives the continuous cigarette roll 21, as it is delivered from the machine. The upper lap of the chain 17 passes over the upper surface of a support 22 which maintains the blocks 19 and grooves 20 in horizontal alinement, and a guide plate 23 extends over the chain to insure the proper feeding of the cigarette roll to the cutter to be hereinafter described.

Certain of the blocks 19, preferably each alternate one, is provided with a ledger blade 24 extending transversely across its front face and supported by a spindle 25 slidably mounted in a recess 26 in the block.

The inner end of the spindle 25 is provided with a threaded bore 27 with which a rotatable threaded pin 28 cooperates to advance or retract the ledger blade.

Cooperating with the successive ledger blades 24 is a helical cutter 29 secured to a shaft 30 which is journaled in the arms of a yoke 31 and provided at one end with a drive pinion 32. The yoke is fulcrumed at 33 and 34 in brackets supported by the frame 10, and is provided at its rear end with an adjusting screw 35 by means of which the cutter 29 may be adjusted upwardly or downwardly into proper relation to the cigarette roll. The pinion 32 is driven by a gear 36 secured to a stub shaft 37, which, in turn, is driven through the worm gear 38 by a countershaft 39 connected by bevel gearing 40 with the shaft 12. The ratio between the several parts of the mechanism for driving the cutter shaft 30 is such that one complete revolution of the cutter 29 will take place while the conveyer chain 17 advances the distance between two consecutive blades 24.

It will be noted, from Fig. 1, that the cutter shaft 30 is so inclined and adjusted that the cutter 29 commences to engage the cigarette roll 21 and gradually cuts into the same during substantially two complete revolutions of the cutter, at which time the cigarette is completely severed at right angles to its longitudinal axis. The lateral in-

clination of the periphery of the cutting plate 29, due to its pitch, is corrected by inclining the axis of the cutter laterally with respect to the cigarette roll, as will be understood from an inspection of Fig. 5. In order to permit this inclination of the cutter shaft and at the same time drive the latter properly from the stub shaft 37, the teeth of the driving pinion 32 may be slightly 10 skewed.

In order that the cigarette machine may be adapted for cigarettes of different lengths, the chain 17 and sprocket wheels 13 and 14 may be replaced by a sprocket 15 gear having the ledger blades spaced at different distances, and the spiral cutter may be replaced by a cutter of different pitch corresponding to the spaces between the ledger blades with which it cooperates. Each cutter 20 shaft will be provided with gearing having the proper ratio for it to operate in unison with the conveyer with which it is used. Provision is made for the easy removal of the cutter shaft by removably securing the bearing 41 for the yoke by means of set screws 42 or the like.

The helical knife may be made right or left handed, according to the direction in which it is rotated by the particular machine with which it is to be used. The movable ledger blades which are carried by the chain 17 are individually adjustable so as to secure their proper cooperation with the helical blade 29, and the edge of the latter 35 is hollow ground to a razor edge, as shown in Fig. 6. Preferably, every alternate block 19 is provided with a ledger blade and each cigarette is supported by a pair of blocks until it is delivered from the machine.

While I have shown and described specifically the structural features of what is at present the preferred form of my invention, it will be understood that various modifications may be made therein so long as such 45 modifications embody the salient features of the invention, as defined by the claims.

What is claimed is:—

1. In a cutting mechanism for cigarette machines, the combination of an endless 50 carrier comprising a series of grooved links for receiving a continuous cigarette roll, certain of said links having ledger blades, a revoluble helical knife cooperating with said ledger blades and having its axis inclined horizontally and vertically with respect to the travel of the conveyer, the vertical inclination being such that after the knife first engages the roll substantially two 55 rotations of the knife are required to complete the cut, and the horizontal inclination being such that the plane of the knife at its active point is perpendicular to the longitudinal axis of the cigarette.

2. In a cutting mechanism for cigarette 60 machines, the combination of an endless 65

carrier comprising a series of grooved links for receiving a continuous cigarette, certain of said links having ledger blades extending transversely across their respective front faces, a revoluble helical knife cooperating with said ledger blades and having its axis inclined horizontally and vertically with respect to the travel of the conveyer, said knife and carrier being so geared together that the carrier advances the distance between two consecutive ledger blades while the knife performs one revolution. 75

3. In a cutting mechanism for cigarette machines, the combination of an endless chain, sprocket wheels on which the chain is carried, blocks secured to the links of the chain and having grooves for receiving a continuous cigarette roll, certain of said links having ledger blades extending transversely across their respective faces, a revoluble helical knife cooperating with said ledger blades, the successive convolutions of the knife being spaced the same distance apart as the distance between two consecutive ledger blades, a common drive shaft 80 for driving the sprocket gear and the knife in timed relation, and means for adjusting the knife toward and away from the chain. 85

4. In a cutting mechanism for cigarette machines, a positively driven endless belt having a succession of substantially equally spaced transverse ledger blades, a revoluble helical cutter cooperating with said ledger blades and driven in timed relation with the endless belt, and means for individually adjusting the positions of the ledger blades forwardly or backwardly to adjust the tension between them and the helical cutter. 90

5. In a cutting mechanism for cigarette machines, a positively driven endless belt having a substantially continuous groove for supporting a continuous cigarette roll and having a succession of substantially equally spaced transverse ledger blades extending across the bottom of said groove, a revoluble helical cutter cooperating with said ledger blade and driven in timed relation with the endless belt, said cutter having substantially two complete convolutions which engage and cut the cigarette during its travel, and means for individually adjusting the positions of the ledger blades forwardly or backwardly. 105

6. In a cutting mechanism for cigarette machines, a positively driven endless belt having a succession of substantially equally spaced transverse ledger blades, a revoluble helical cutter cooperating therewith and driven in timed relation with the endless belt, means for individually adjusting the positions of the ledger blades forwardly or backwardly, and means for adjusting the cutter toward and away from the belt. 110

7. In a cutting mechanism for cigarette machines, an endless conveyer composed of links formed on their upper lap with a sub- 125

stantially continuous groove for receiving the continuous cigarette roll, certain of said links having ledger blades extending transversely across their front faces, a revoluble 5 helical knife cooperating with said ledger blades and having its axis inclined horizontally and vertically with respect to the

travel of the conveyer, and means for individually adjusting said ledger blades forwardly or backwardly to vary the tension 10 between the same and the helical knife.

In testimony that I claim the foregoing as my own, I have hereto affixed my signature.

CHARLES EMMETT WEISNER.
